C. L. S. ATTORNEY.

UNITED STATES PATENT OFFICE.

SAMUEL SELDEN, OF DENVER, COLORADO.

LIFTING JACK.

1,413,793.

Specification of Letters Patent. Patented Apr. 25, 1922.

Application filed April 6, 1921. Serial No. 452,939.

To all whom it may concern:

Be it known that I, SAMUEL SELDEN, a citizen of the United States, residing at Denver, in the county of Denver and State of Colorado, have invented certain new and useful Improvements in Lifting Jacks, of which the following is a specification.

This invention relates to lever jacks of the double action type in which two pawls are carried on an operating lever at opposite sides of the fulcrum thereof to alternately lift the load by up and downward movement of the same.

The main object of the present invention is to provide in a jack of the above described character, a reversing device of simple construction which in an adjusted position operates to separate the pawls alternately from the teeth of the rack-bar with which they normally engage, for the purpose of lowering the load by the reciprocating motion of the operating lever.

Another object of the invention is to provide in connection with the reversing mechanism, springs which act upon the pawls to maintain them in operative relation to the rack bar during the lifting action, and still other objects reside in the construction and arrangement of parts shown in the accompanying drawings in the several views of which corresponding parts are similarly designated and in which—

Figure 1 is a side elevation of a lifting jack to which the improved reversing mechanism is applied;

Figure 2, a section taken on the line 2—2, Figure 1;

Figure 3, a fragmentary sectional elevation of the operating parts of the jack in the position occupy during the lifting action;

Figure 4, a view similar to Figure 3 showing the reversing device in its operative relation to the lifting pawls which are shown in their position at the end of the down stroke of the lever;

Figure 5, a view similar to Figure 4 showing the parts in their position at the end of the up-stroke of the lever;

Figure 6, a fragmentary elevation of the jack with part of the side plate of its housing broken away to show the eccentric movement of the reversing mechanism;

Figure 7, a similar view after the eccentric adjusting element of the mechanism is removed;

Figure 8, a view similar to that of Figure 3, showing a modified construction of the reversing mechanism;

Figure 9, a view similar to Figure 6 showing the position of the eccentric movement of the reversing mechanism of the construction shown in Figure 8, and

Figure 10 a sectional elevation of the operating parts of the jack showing the reversing mechanism equipped with springs which hold the pawls in engagement with the rack bar during the lifting action.

Referring to the drawings by numerical characters of reference the improved lifting jack comprises a standard 5 of ordinary form and construction in which a rack bar 6 has a vertical sliding movement. A plate 7 detachably fastened at a side of the standard covers a housing in which the parts of the lifting and reversing mechanisms are cooperatively assembled.

The operating lever of the jack which as usual is composed of a metal socket 8 and a wooden handle 9 removably inserted therein, is fulcrumed on the standard by means of a transverse pin 10 and it has two shoulders 12 and 13 which limit its reciprocating movement by engagement with a corresponding part of the standard and one of the lifting pawls hereinafter to be described.

The operating lever has at opposite sides of its fulcrum open seats adapted to support the trunnioned ends of two lifting pawls 14 and 15 which are positioned with relation to the rack bar to constantly engage the teeth thereof by gravity.

In the operation of the jack to lift a load supported on the rack-bar, the downward stroke of the lever causes the lower and shorter pawl 14 to raise the rack-bar while the other, longer pawl 15 rides idly across the teeth thereof and when the movement of the lever is reversed the upper pawl is forced to act upon the rack bar while the other pawl inactively returns to its original position.

The reversing mechanism of the present invention by which the pawls are caused to alternately sustain the load on the rack bar during its downward movement, comprises a carrier 16 which by means of a laterally projecting pin 17 is slidably supported in a horizontal slot 18 of a plate 19 which is fastened inside the housing of the standard in spaced relation to the before-mentioned closing plate 7.

An eccentric 20 rotatably supported on the

pin is held in place by a head at the outer end thereof and it has forwardly projecting thumb wings inside an opening of the cover plate to facilitate its rotation for the purpose of sliding the carrier in the slot of the plate 19.

The eccentric is movably fitted inside a ring 21 formed at the end of a radial extending arm 21^a which at its outer extremity is 10 pivotally supported on the plate 19 by means of a screw pin 28.

Attached at one of their ends respectively at the upper and lower sides of the carrier are two forwardly projecting leaf springs 15 22 and 23 which in the operative position of the reversing device are respectively engaged by studs 24 and 25 which project laterally from the two lifting pawls.

The upper spring curves upwardly and 20 extends below the respective stud of the upper pawl, and the lower spring which extends partially above the stud of the pawl 14 has a reversely bent end portion 23^a extending slantingly beneath the same.

25 When the jack is used to lift the load the carrier is in its extreme forward position in which the springs are out of the paths of travel of the respective studs of the pawls when by up and downward movement of 30 the lever the latter are operated to alternately act upon the rack bar as hereinbefore described.

It will thus be seen that in the operation 35 of the jack as a lifting medium, the springs of the reversing device are idle and that gravity is the only force relied upon to maintain the pawls in engagement with the teeth of the rack bar. However, should varying conditions require the use of springs 40 to constantly maintain the operative relation of the pawls to the rack bar, they may be readily applied to the sliding carrier of the reversing mechanism as shown in Figure 10 of the drawings in which two additional springs 26 and 27 attached at the upper 45 and lower ends of the carrier by the same fastening means which secure the beforementioned springs 22 and 23, are formed to respectively bear upon the studs on the pawls when the reversing device is in its inoperative position.

When it is desired to lower the load upon the rack-bar, the pawls are employed to alternately sustain the weight thereof during 55 their downward motion in the reciprocating movement of the operating lever, through the medium of the springs 22 and 23 on the sliding carrier after the latter has been adjusted by rotation of the eccentric 60 to its operative position illustrated in Figures 4 and 5.

When with the parts in this position the operating lever is reciprocated the springs are alternately engaged by the respective 65 studs on the pawls and so deflected that at

the termination of each stroke of the lever one of the pawls is forced out of engagement with the teeth of the rack bar. To be more specific, when the upper pawl is lowered by downward movement of the lever it sustains the downwardly moving load on the rack bar by engagement with the teeth thereof while the lower pawl which previously was separated from the rack bar by the action of the spring 23 as will hereinafter be described, is gradually returned to its original position by the movement of its stud along the slanting terminal portion of the spring.

The stud on the upper pawl has meanwhile engaged the upper spring on the carrier and gradually deflects it to the position shown in broken lines in Figure 4 until the lever reaches the end of its downward stroke when under the law of restitution it causes the pawl to disengage the teeth of the rack bar and move it to the position shown in full lines in the same view.

When the lever is subsequently moved upwardly the downwardly moving lower pawl 90 sustains the load on the rack bar while the upper pawl gradually approaches the rack bar by the movement of its stud along the upwardly curving portion of the upper spring until at the end of the stroke it has again 95 moved in engagement with the teeth thereof. The stud on the lower pawl is in the meantime brought in engagement with the terminal part of the lower spring which thereby is deflected as shown in broken lines in 100 Figure 5 and which when the lever reaches the end of its upward movement, causes the pawl to disengage the teeth of the rack bar and moves it to the position shown in full lines in Figure 5.

105 In the modified construction shown in Figures 8 and 9 of the drawings, the carrier is adjusted vertically instead of horizontally to bring its springs in operative relation to the studs on the lifting pawls. The springs 110 are of slightly different form from those of the first-described construction, the slot in the plate 19 in which the carrier is guided extends vertically instead of horizontally, and the ring around the eccentric is fastened 115 at right angles to its former position.

The operation of the modified reversing device is the same as that hereinbefore described with relation to the original construction, the position of the springs on the 120 carrier in the operative position thereof having been shown in broken lines in Figure 8.

Having thus described my invention what I claim and desire to secure by Letters-Patent is:

125 1. In a lifting jack, the combination of a rack-bar, lifting pawls engaging the teeth thereof, a lever in operative relation to the pawls, and a reversing device comprising an adjustable carrier, and springs on the 130

carrier normally disengaged from the pawls and adapted to engage the pawls in an adjusted position of the carrier to alternately force them out of engagement with the teeth 5 of the rack bar in the operation of the jack by movement of the lever.

2. In a lifting jack, the combination of a rack-bar, lifting pawls engaging the teeth thereof, a lever in operative relation to the 10 pawls, and a reversing device comprising an adjustable carrier, spring-members on the carrier normally disengaged from the pawls and adapted to engage the pawls in an adjusted position of the carrier to alternately 15 force them out of engagement with the teeth of the rack bar in the operation of the jack by movement of the lever, and a spring member on the carrier which in its normal position engages the pawls to hold them in 20 engagement with the rack bar.

3. In a lifting jack, the combination of a rack-bar, lifting pawls engaging the teeth thereof and having laterally projecting studs, a lever in operative relation to the 25 pawls, and a reversing device comprising an adjustable carrier, and springs on the carrier normally disengaged from the studs and adapted to bear upon the studs when the carrier is in its adjusted position, to 30 alternately lift the pawls out of engagement with the teeth of the rack bar in the operation of the jack by movement of the lever.

4. In a lifting jack, the combination of a rack bar, lifting pawls engaging the teeth 35 thereof and having laterally projecting studs, a lever in operative relation to the pawls, and a reversing device comprising an adjustable carrier, spring-members on the carrier normally disengaged from the 40 studs and adapted to engage with the same in an adjusted position of the carrier to alternately force them out of engagement with the teeth of the rack bar in the operation of the jack, and a spring member on the carrier which in 45

its normal position, engages the studs to hold the pawls in engagement with the rack bar.

5. In a lifting jack, the combination of a rack bar, lifting pawls engaging the teeth thereof, and having laterally projecting 50 studs, a lever in operative relation to the pawls, and a reversing device comprising an adjustable carrier, and springs on the carrier having slanting portions adapted to engage with the studs on the pawls, in an 55 adjusted position of the same.

6. In a lifting jack, the combination of a rack bar, lifting pawls engaging the teeth thereof, and having laterally projecting 60 studs, a reciprocating lever in operative relation to the pawls, and a reversing device comprising an adjustable carrier, and springs on the carrier normally disengaged from the studs and adapted to engage with the same in the adjusted position of the 65 carrier to alternately disengage the pawls from the teeth on the rack bar at the ends of the reciprocating movement of the lever.

7. In a lifting jack, the combination of a rack bar, lifting pawls engaging the teeth 70 thereof, an operating lever, and a reversing device comprising a sliding carrier and slanting springs on the carrier adapted to engage with projections on the pawls in an adjusted position of the same. 75

8. In a lifting jack, the combination of a rack-bar, lifting pawls engaging the teeth thereof, a lever in operative relation to the pawls, and a reversing device comprising a sliding carrier, and springs on the carrier 80 normally disengaged from the pawls and adapted to engage the pawls in an adjusted position of the carrier to alternately force them out of engagement with the teeth of the rack-bar in the operation of the jack 85 by movement of the lever.

In testimony whereof I have affixed my signature.

SAMUEL SELDEN.
